UNITED STATES PATENT OFFICE.

HENRY J. HOUTSINGER AND HERBERT A. STILSON, OF ROCK FALLS, ILLINOIS, ASSIGNORS, BY MESNE ASSIGNMENTS, TO STERLING SPECIALTY COMPANY, OF STERLING, ILLINOIS, A CORPORATION OF ILLINOIS.

TRAP.

No. 849,070.

Specification of Letters Patent.

Patented April 2, 1907.

Application filed February 27, 1906. Serial No. 303,163.

To all whom it may concern:

Be it known that we, HENRY J. HOUTSINGER and HERBERT A. STILSON, citizens of the United States, residing at Rock Falls, in the county of Whiteside and State of Illinois, have invented a new and useful Improvement in Traps, of which the following is a specification.

Our invention relates particularly to traps for vermin of the character of rats, mice, or the like.

Our primary object is to provide a trap of the character indicated capable of resetting itself after being sprung, whereby the trap will operate a number of times without attention or until its power is exhausted.

The invention is illustrated in its preferred embodiment in the accompanying drawings, in which—

- 20 Figure 1 represents a side elevational view of our improved trap; Fig. 2, an opposite side elevational view; Fig. 3, a vertical sectional view taken as indicated at line 3 of Fig. 4; Fig. 4, a plan view of the device; Fig. 5, a broken vertical section taken as indicated at line 5 of Fig. 4; Fig. 6, a broken horizontal section taken as indicated at line 6 of Fig. 5, and Fig. 7 a broken horizontal section taken as indicated at line 7 of Fig. 2.
- 25 In the embodiment shown the device comprises a casing or frame A, a rotary shaft B, journaled in the upper portion of the casing and equipped with a striker B', a coil-spring B², having its inner end secured to the shaft B and its outer end secured to a stud B³, projecting inwardly from one side of the casing, trip mechanism C, controlling the striker and equipped with a spring C', a tension-relieving device C², carried by the shaft B and serving
- 30 to automatically relieve the spring tension upon the pedal of the trip mechanism after the arrest of the striker by the trip mechanism, a stationary stop C³, coacting with an automatically projected and retracted stop C⁴, carried by the tension-relieving device C², and a bait-receptacle D, connected with the casing A adjacent to the free end of the trip mechanism.
- 35 The casing A preferably comprises side members a and a bottom member a', the ends and top of the casing being open. The sides

of the casing are separated by a comparatively narrow space sufficient, however, to enable a small animal to enter.

The shaft B comprises a bolt journaled in 55 and projecting through the casing, as shown. The striker B' comprises a metal bar b, lying adjacent to the inner surface of one side of the casing and secured at its center upon the shaft B to rotate therewith. The end portions of the bar are twisted and bent to form striking members b', extending in a transverse plane and approximately of a width equal to the space between the side members of the casing. It will be understood that the 60 striker is rotated through the medium of its shaft and the spring connected therewith when the trip mechanism is operated to release the striker. The bar-form body of the striker is confined between one side of the 65 casing and the spring B², as clearly appears from Fig. 4. The stud B³ is short enough to allow space between its extremity and the adjacent side of the casing to permit rotation of the striker.

The trip mechanism C, comprises a vertical lever c, supported at its upper end on a pivot c' and constituting a closure for one end of the casing, a small bell-crank lever c², supported on the pivot c' and having an arm 80 c³, adapted to engage an end of the striker, and an arm c⁴, adapted to bear against the lever c beneath the pivot c', a spring c⁵, serving to maintain the bell-crank lever c² in operative position with its arm c⁴ bearing 85 against the lever c, a pedal c⁶, substantially parallel with the bottom of the casing and supported centrally on a pivot c⁷, extending transversely across the casing near the bottom thereof, a catch c⁸, carried by the rear 90 end of the pedal and engaging a slot c⁹ in the lower end of the lever c, the member c⁸, having at its inner end a downwardly-projecting extension c¹⁰, affording a stop which rests upon the bottom of the casing, a lever c¹¹, 95 supported on a pivot c¹², extending across the casing adjacent to the lower end of the lever c and having a downwardly-curved front end c¹³, and links c¹⁴ c¹⁵, connecting the lever c¹¹ with the central portion of the lever c. The 100 spring C' has an arm c¹⁶, which extends along the exterior of one side of the casing in the

path of the tension-relieving device C², said arm having an upcurved extremity c¹⁷, from which depends a member c¹⁸, having an in-turned arm c¹⁹, which extends through an opening c²⁰ in the casing and is positioned beneath the free end of the pedal c⁶. The arm c¹⁶ is carried by a coil c²¹, from which projects inwardly a pivotal portion c²², which extends through the casing near the rear end 5 thereof and is equipped on the opposite side of the casing with an arm c²³, having an in-turned extremity c²⁴, which may be caused to engage any one of a series of perforations c²⁵, with which the adjacent side of the casing 10 is provided. The series of perforations c²⁵ is for use in adjusting the tension of the spring. 15

The tension-relieving device C² comprises a sheet-metal member or bar c²⁶, fixedly secured on the shaft B outside of the casing 20 above the free end of the arm c¹⁶ of the spring C', an arm c²⁷, journaled on the shaft B outside the member c²⁶ and equipped with a leaf-spring c²⁸, having its upper free end turned inwardly to afford a cam c²⁹, projecting 25 through a slot c³⁰ in the arm c²⁷, said cam having a sloping surface c³¹, and the stop C⁴ in the form of a slide connected with the lower end of the arm c²⁷ and normally held in 30 its elevated or retracted position by means of a spring c³², connected with the slide and with the arm c²⁷, the limit of movement upwardly of said slide being a stop c³³, with which the arm c²⁷ is provided, as shown in Fig. 5. The lower end of the arm c²⁷ is provided with an outwardly-turned downwardly-curved arm c³⁴, affording on its lower side a groove or cam which engages the arm c¹⁶ of the spring C'. The opposite lateral edges of the member c²⁶, which rotates with the shaft 35 40 B, affords abrupt shoulders at points c³⁵, which serve to engage an abrupt shoulder c³⁶ on the inwardly-projecting end c²⁹ of the leaf-spring c²⁸, thereby to cause the arm c²⁷ to rotate with the member c²⁶. The member c²⁶ is further provided at points opposite the points c³⁵ with struck-in portions c³⁷, affording sloping surfaces over which the sloping surface c³¹ of the spring c²⁸ may ride, so that the arm c²⁷ may continue to rotate under its 45 50 own inertia after the striker has been arrested by the trip mechanism and the member c²⁶ has come to a rest with the striker. When the shaft comes to a stop, owing to the arrest of the striker by the trip mechanism, the arm c²⁷ continues to rotate under its own momentum until it comes to the position shown in Fig. 1, the slide C⁴ being projected during this movement under its acquired momentum and the centrifugal force acting 55 60 upon it, the slide moving to the position indicated in dotted lines so as to engage the stationary stop C³. After the arm c²⁷ is arrested by the stop C³ the slide C⁴ is retracted by its spring and the member c³⁴ then 65 holds the free end of the arm c¹⁶ depressed,

thereby holding the arm c¹⁶ of the spring out of contact with the free end of the pedal c⁶, as shown in Fig. 3.

The bait-chamber D comprises a box having a tongue d, removably entered in a loop d', with which the casing A is provided. The inner side of the box D, as indicated in Fig. 7, is open, as indicated at d², and this opening registers with an opening d³ in the casing A adjacent to the pedal c⁶. It is necessary for 75 an animal attempting to secure bait—say a piece of cheese placed in the receptacle D—to step upon the pedal c⁶, and thereby spring the trap.

The casing A is equipped at one end of its 80 bottom with arms or supports E, connected with the casing-bottom by pivots e and having flanges e', affording shoulders e², which abut against the sides of the casing when the arms are in the extended position. When desired, the arms E may be turned upon their pivots to fold them beneath the bottom of the casing with the flanges e' adjacent to the sides of the casing.

The operation may be briefly summarized. 90 The spring B² may be wound by turning the striker B' in a direction opposite the direction indicated by the arrow in Fig. 3, the bell-crank lever c² working idly to permit the arms of the striker to pass it. During the winding 95 operation the tension-relieving device of the trip mechanism may be moved to the right from the position shown in Fig. 1, so as to allow the full pressure of the spring upon the pedal of the trip mechanism, so that in the 100 event of accidental slippage of the striker from the hand of the person winding the device the striker would be arrested by striking against the bell-crank lever c². After the winding operation the tension-relieving device 105 may be revolved in the direction indicated by the arrow in Fig. 1 until it occupies the position shown in Fig. 1, thereby depressing the free end of the arm c¹⁶ of the spring C' and relieving the tension upon the pedal c⁶. 110 With the trap in this condition a mouse entering to nibble at the cheese placed in the receptacle D would depress the free end of the pedal c⁶, thereby releasing the lever c and permitting the striker to be rotated through the 115 medium of its shaft and the spring B² connected therewith. The striker would thereupon make a half-revolution, encountering the arm c¹¹ during this movement and drawing the lever c to the closed position, where it 120 is engaged by the catch c⁸ of the pedal c⁶, it being understood that during the initial movement of the striker the member c²⁶ engages the spring c²⁸ of the tension-relieving device and frees the tension-relieving device 125 from the arm c¹⁶ of the spring C', so that the full pressure of the spring is upon the pedal, insuring the proper action of the trip mechanism in arresting the movement of the striker. After the movement of the striker is arrested 130

the tension-relieving device continues to rotate until it comes to the position shown in Fig. 1, relieving the tension upon the pedal of the trip mechanism, leaving the trip mechanism free to be operated again. The striker moves with such force as to deal an instantaneously fatal blow to the mouse and eject it from the casing, so that the trap is immediately in readiness for a second operation.

10. It will be understood that the purpose of the tension-relieving device is to enable a stiff spring to be used in connection with the trip mechanism for the purpose of assuring the arrest of the striker after it has made a 15 half-revolution, it being necessary under such conditions to then relieve the tension upon the trip mechanism to enable the trap to be sprung. The purpose of the lever c^{11} is to insure the inward movement of the lever c 20 in time to make engagement with the pedal c^6 before the striker has completed a half-revolution. It would be difficult, if not impossible, to secure the desired result by using a spring for the purpose.

25. Many changes in details of construction within the spirit of our invention are feasible, as will be readily understood. Hence the foregoing detailed description is understood to be made for clearness of understanding 30 only.

What we regard as new, and desire to secure by Letters Patent, is—

35. 1. A trap comprising a striker, stored-power mechanism for actuating the striker, trip mechanism equipped with a spring, and automatic means for relieving the tension of the spring upon the trip to enable it to be easily sprung.

40. 2. A trap comprising a striker, stored-power mechanism for actuating the striker, trip mechanism equipped with a spring, a tension-relieving device equipped with an automatically-actuated stop, and a stop with which said first-named stop makes automatic engagement and disengagement.

45. 3. A trap comprising a potentially-movable rotary striker, spring-equipped trip mechanism automatically arresting the striker in its rotation, and automatic means for relieving the tension of the trip mechanism.

50. 4. A trap comprising a potentially-movable rotary striker, trip mechanism equipped with a spring, and a tension-relieving device for relieving the pressure of said spring upon the trip mechanism comprising a rotary member actuated with the striker and moving under its own inertia after the arrest of movement of the striker to relieve the pressure of the spring upon the trip mechanism, for the purpose set forth.

55. 5. A trap comprising a potentially-movable rotary striker, trip mechanism equipped with a spring, a member rotating with the 60 striker, a tension-relieving member, and co-

operating means on said two members for moving the second-named member through the medium of the first-named member and permitting a continuation of said movement after the first-named member has come to a 70 rest, whereby the tension of said spring upon the trip mechanism is relieved after the arrest of the striker, for the purpose set forth.

6. A trap comprising a potentially-movable rotary striker, a member secured to and 75 rotating with the shaft of said striker, trip mechanism serving to arrest said striker at each half-revolution, and a tension-relieving member actuated by the member secured to said shaft and making a complete revolution 80 at each half-revolution of the striker.

7. A trap comprising a potentially-movable rotary striker, a member secured to and rotating with the shaft of said striker, trip mechanism serving to arrest said striker at 85 each half-revolution, and a tension-relieving member equipped with a spring engaged by the member secured to said shaft, said spring serving as a means for actuating the tension-relieving member and the tension-relieving 90 member being movable after the arrest of movement of the member secured to said shaft, for the purpose set forth.

8. A trap comprising a shaft a potentially-movable rotary striker mounted on the 95 shaft, trip mechanism equipped with a spring, a tension-relieving member journaled on said shaft, and means actuated by the shaft for giving an impetus to the tension-relieving member during the movement of 100 said striker, for the purpose set forth.

9. A trap comprising a potentially-movable rotary striker, trip mechanism operating to arrest said striker at each half-revolution, a shaft for said striker, a spring for the 105 trip mechanism, a spring-engaging member journaled on said shaft, means actuated by the shaft for giving an impetus to said spring-engaging member, and a yieldingly-held automatically-projected stop carried by 110 the spring-engaging member, for the purpose set forth.

10. A trap comprising a shaft a potentially-movable rotary striker mounted on the shaft, trip mechanism for the striker including a pedal, a spring adapted to exert pressure upon the pedal, a spring-engaging member journaled on said shaft, means carried by the shaft for giving an impetus to said spring-engaging member, a stationary stop, and a 115 stop movably connected with the spring-engaging member, for the purpose set forth.

11. A trap comprising a casing, a shaft a potentially-movable rotary striker mounted on the shaft journaled in said casing, trip 120 mechanism including a substantially vertical lever at one end of the casing and a substantially horizontal pedal engaging said lever, a spring adjustably connected with the said casing and having a forwardly-projecting arm 125 130

equipped with a projection adapted to engage said pedal, a tension-relieving member journaled on said shaft adapted to engage said spring, and means connected with said shaft 5 for giving an impetus to the tension-relieving member, for the purpose set forth.

12. A trap comprising a casing having an open end, a potentially-movable striker pivoted in the upper portion of said casing, and 10 trip mechanism comprising a lever pivotally connected with the upper portion of the opposite end of said casing, a bell-crank lever engaging said first-named lever and having an arm supporting the striker, said bell-crank lever being movable idly in one direction, and a pedal controlling said first-named lever.

13. A trap comprising a casing having an open vertical end, a coil-spring connected 20 with said casing, a horizontal shaft connected with said coil-spring and equipped with arms swinging in a vertical plane and constituting a striker, and trip mechanism comprising a lever forming a closure for the 25 opposite end of the casing, and a pedal controlling said lever.

14. A trap comprising a casing, a potentially-movable rotary striker mounted in the upper portion thereof, and trip mechanism 30 comprising a lever with means for engaging the striker, a pedal controlling said lever, and a lever adapted to move said first-named lever to the closed position and projecting into the path of the striker.

15. A trap comprising a potentially-movable rotary striker, trip mechanism comprising a lever with means for arresting the striker, a lever connected with said first-named lever and projecting into the path of 35 the striker, a pedal controlling said first-named lever, a spring for exerting pressure upon the pedal, a tension-relieving device, and means moving with the striker for giving an impetus to said tension-relieving device, 40 for the purpose set forth.

16. A trap comprising a casing, a potentially-movable rotary striker mounted on a horizontal pivot in the upper portion thereof, said casing having an open vertical end, and trip mechanism comprising a lever constituting 50 a closure for the other end of the casing, and a pedal within the lower portion of said casing controlling said lever.

17. A trap comprising a casing having an open end, a potentially-movable striker 55 mounted in the upper portion of said casing, a bait-chamber opening within the casing, and trip mechanism comprising a substantially vertical lever supporting the striker, and a substantially horizontal pedal having its free 60 end adjacent to the bait-chamber, for the purpose set forth.

18. A trap comprising a casing having an open end and an opening at one side, a potentially-movable rotary striker mounted in 65 the upper portion of the casing, a removable bait-chamber connected with the side of the casing at the opening therein, and trip mechanism comprising a member affording a closure for the opposite end of the casing, and 70 a pedal controlling said member.

19. A trap comprising a casing having an open end, a potentially-movable rotary striker mounted in the upper portion of the casing and having a rearwardly-extending 75 arm, a lever pivoted at the upper portion of the rear end of the casing constituting a closure for the rear end of the casing, a bell-crank lever pivoted at the same point and engaging the striker-arm and having a bearing on said first-named lever, and a pedal within the casing near the bottom thereof, and having engagement at its rear end with the lower end of said first-named lever, for 80 the purpose set forth.

HENRY J. HOUTSINGER.
